UNITED STATES PATENT OFFICE.

HENRY V. COLEMAN, OF CHICAGO, ILLINOIS.

IMPROVEMENT IN APPARATUS FOR WARMING STEAM-FIRE-ENGINE HOUSES,

Specification forming part of Letters Patent No. 150,938, dated May 19, 1874; application filed April 16, 1874.

To all whom it may concern:

Be it known that I, HENRY V. COLEMAN, of Chicago, in the county of Cook and State of Illinois, have invented an Improvement in Apparatus for Warming Steam-Fire-Engine Houses, of which the following is a specification:

The nature of this invention relates to the combination, with the circulating water-heating apparatus used in engine-houses for keeping the water in the fire-engine boiler hot ready to generate steam, of hot-water coils and radiators, for warming the engine-room during cold weather by the waste heat; it also relates to a novel method of warming the upper rooms by the columns of air passing up through the boiler-tubes, the entire interior surface of the boiler serving as a radiator to heat the ascending air-currents, so that the engine-house may be kept comfortably warmed, without the expense of operating stoves or a furnace for that purpose.

Figure 1 is a perspective view, showing portions of the main and upper floors of an engine-house; it also shows the heater in the basement, a portion of the fire-engine on the main floor, and the arrangement of the hot-water pipes. Fig. 2 is a partial cross-section of the upper floor at the register, and a vertical section of the hot-air flues and chimney-hood.

In the drawing, A represents the boiler of a steam fire-engine, standing in its place in the engine-house. B is a hot-water coil or radiator. C is the circulating water-heating boiler in the basement, such as is used for keeping the water in the engine-boiler hot. L is the service-pipe and cock for supplying it with water when needed. D is a register in the upper floor directly over the smoke stack of the engine when the latter is in proper place. From the register is suspended a flue, D¹, which may have one or more lateral flues leading to other rooms overhead. In the lower end of the flue is sleeved a hood, D², suspended from a cord, a, passing over guide-pulleys b b, and down to a lever, G, below the main floor. F is the flow-pipe from the heater, and R is the return-pipe thereto. The former terminates in a three-way cock, c, whose plug is actuated by the lever G. From the cock c

issues a rising flow-pipe, F¹, coupled by a slip-joint, f, to the flow-pipe F² of the engine-boiler. R² is the return-pipe from the said boiler, connected by a slip-joint, f', with a drop return-pipe, R¹, which enters a three-way cock, d, to whose end is connected the flow-pipe B¹ of the coil B. To the other outlet of the cock d is connected the bent upper end of the return-pipe R of the heater. The return-pipe B² of the coil is connected by a T with a pipe, F³, one end of which communicates with the cock e, and the other with the bent end of the return-pipe R; but between the latter and the T is a stop-cock, e, actuated by the lever G. The cock c is actuated by a lever, H, which, with the lever G, is connected or pivoted to the lower end of a rod, I, which projects up through the floor. The engine being in the position shown, and the rod I pushed down, hot water issuing from the heater C through the pipe F will pass through the cock e and pipes F¹ F² into the engine-boiler. The colder water will issue from said boiler through the return-pipes R² R¹, passing through the cock d and pipe B¹ into the coil B, returning through the pipes B² F³, stop-cock e, and return-pipe R, to the bottom of the heater-boiler, the course of the currents being indicated by arrows in Fig. 1. The colder air near the floor passes up through the fire-box and tubes of the engine, where it is warmed by contact with the heated metal. Issuing from the smoke-stack it passes through the hood D², flue D¹, and register D, into the men's sleeping-room above; or a portion of the heated air may be taken by a lateral flue to another room, as indicated in Fig. 2. When the engine is to leave the house the rod I is pulled up to shut off the flow to and from the engine through the cocks c d, and to close the cock e; at the same time the hood D² is lifted clear of the stack. The water now issuing from the heater will rise through the pipe F and cock e, and pass through the pipe F³ into the pipe B², thence through the coil B, back through B¹, d, and R, to the heater, reversing the flow through the coil. M is a gage on the coil to indicate the water-pressure.

What I claim as my invention, and desire to secure by Letters Patent, is—

1. The combination, with a steam fire-engine

and a fire-engine water-heater, of one or more hot-water coils, B, substantially as described, and for the purpose of heating the engine-room, as set forth.

2. The combination of the pipes B B¹ B² with the cocks c d e, and pipes F F¹ F² F³ R R¹ R², levers G H, and rod I, as and for the purpose set forth.

3. The register D, flue D¹, and hood D², in

combination with a steam fire-engine and water-heater pipes, for the purpose of heating one or more rooms above the engine-room, substantially as shown and set forth.

HENRY V. COLEMAN.
